August Pann.
by A. A. Thomas
Atty.

UNITED STATES PATENT OFFICE.

AUGUST PANN, OF BROOKLYN, NEW YORK.

HOUSEHOLD-TOOL FOR REPAIRING THE VALVE-SEATS OF FAUCETS AND THE LIKE.

1,271,608.

Specification of Letters Patent. Patented July 9, 1918.

Application filed February 21, 1918. Serial No. 218,384.

To all whom it may concern:

Be it known that I, AUGUST PANN, a citizen of the United States, and a resident of Brooklyn, in the county of Kings and State 5 of New York, have invented certain new and useful Improvements in Household-Tools for Repairing the Valve-Seats of Faucets and the like, of which the following is a specification.

10 The object of my invention is to provide a tool, complete in itself, which every householder can use to repair the worn valve-seats of faucets. It is a well-known fact that after the ordinary water faucets, such 15 as are found in dwellings, have been in use for some time, the circular seat or ring against which the washer of the valve stem bears, becomes worn and presents an irregular or uneven surface to the washer. The 20 result is that the washer, which is usually of leather, fiber or hard rubber, can no longer make the faucet water-tight. This condition cannot be remedied by the mere insertion of a new washer, because the leakage is 25 due to the uneven surface of the valve-seat on which the washer bears. Heretofore, the householder having no tool at his command with which to repair the worn or defective valve-seat, either had to send for the plumber 30 to repair the seat, or else had to buy an entirely new faucet, or at least an entirely new stem for the same. In either case the householder was put to considerable expense.

The tool of my present invention is primarily intended to be an aid to the householder and enable him to repair a worn or defective valve-seat in a faucet, without having to go to the expense of securing a plumber to do it for him, or of buying a new 40 faucet.

A preferred embodiment of my invention is illustrated in the accompanying drawings in which—

Figure 1 shows a tool embodying my invention, in position to repair the worn valve-seat of a faucet, certain parts being shown in cross-section for the sake of clearness;

Fig. 2 is a top plan view taken approximately on line 2—2 of Fig. 1; and

50 Fig. 3 is a detailed view showing the cutting member of my repair tool in cross-section and also showing an additional ring surrounding the cutting member when the tool is used to repair a faucet of a larger 55 internal diameter than that shown in Fig. 1.

In Fig. 1, the letter F represents a faucet

of ordinary construction, such as are used in almost every house. The valve-stem which engages with the screw-threaded portion *f* of the faucet is omitted from the 60 drawings, as its construction and operation are understood by everybody. It is only necessary to say here that the reference letter *v* indicates the circular valve-seat or ring 65 against which bears the washer carried by the lower end of the valve-stem. When the faucet is turned off, the washer rests firmly against the seat or ring *v*, thereby completely shutting off the water.

As previously stated, the valve-seat or 70 ring *v* becomes worn after a time, and thus presents an uneven or irregular surface at the top, so that the washer at the lower end of the valve-stem can no longer shut off the water without leakage. The tool which constitutes my present invention is designed 75 to smooth off the upper surface of the valve *v* and make the same practically as good as new. To this end, my invention comprises in its preferred form, a stem 1. provided at its lower end with a cutter indicated as a whole by C. This cutter consists of a tubular or sleeve member provided at its lower end with cutting teeth 2 adapted to engage the valve *v* when the tool is operated, as hereinafter described. The cutter C, which fits snugly on the stem 1, is provided with one or two slots or recesses 3 which engage the transverse pin 4 fixed upon the stem 1. This pin-and-slot engagement 80 prevents the cutter from dropping off the stem, as when the tool is lifted 85 out of the faucet. I provide a set screw 5 which bears at its inner end against the stem. A slight turn of the screw 5 will unlock the cutter and permit the same to be slid off the 90 stem when desired.

The upper end of the stem 1 is provided with a rotatable head or knob indicated as a whole by K, by means of which the operator, by placing his hand thereon, is able 105 to exert the required downward pressure on the stem to impart a cutting action to the teeth 2 of the cutter C. It will be understood that unless sufficient downward pressure is brought to bear on the stem 1, the cutter cannot perform its function of smoothing 110 the valve *v*. The head or knob K may be of

any suitable construction. In the drawings I have shown the head K, which is preferably of wood, formed with a circular flange 6. On the inside, this flange is surrounded 5 by a bearing collar 7 of metal, and on the outside by a metal strengthening ring 8. An adjustable screw 9 passes through the parts 8, 6 and 7 and terminates in the groove 10 formed in the stem 1. In this way the head 10 K is rotatably mounted on the stem 1, and yet is prevented from sliding longitudinally of the stem. To remove the head K it is only necessary to turn the screw 9 until its 15 inner end has passed out of the groove or channel 10.

Midway of its length, the stem 1 has rigidly mounted thereon a ratchet 11. This rigid connection between the stem and the ratchet is diagrammatically indicated in Fig. 2 by 20 the key 11' in dotted lines. Below the ratchet 11, and spaced therefrom, is a collar 12 which is shown fixed to the stem by means of a removable pin 13. Between the ratchet 11 and the collar 12 is mounted a suitable 25 handle-bar indicated as a whole by H. The handle-bar H, the outer or free portion of which is shown broken away in Figs. 1 and 2, carries a pawl 14 which is pivoted on the handle-bar by a pivot 15. The pawl 14 is 30 so arranged that its free end engages the teeth of the ratchet 11. Suitable spring means is provided for urging the pawl against the teeth of the ratchet. In the drawing, I have shown spring means in the 35 form of a small coil spring 16 which bears at one end in a recess 17 in the pawl 14, as indicated in dotted lines in Fig. 2, and which bears at its outer end against a suitable support 18. In the particular form of 40 my invention shown in the drawings, the spring-supporting member 18 projects from the forward edge of the handle-bar H, as indicated at 19 in Figs. 1 and 2, being then curved upwardly at an angle into such position 45 that it terminates in alignment with the pawl 14, so that the spring 16 is firmly held between the pawl and the free end of the member 18. Any other suitable spring means may be employed for normally holding the 50 pawl 14 against the teeth of the ratchet 11.

The operation of my new tool will be clear from the foregoing and may be briefly stated as follows: After the tool has been placed in position as shown in Fig. 1, the handle-bar 55 H is pulled toward the operator—that is to say, in a clockwise direction, as indicated by the arrow a in Fig. 2. This movement of the handle-bar H, which may be called its forward or operative movement, produces a 60 corresponding movement of the stem 1 and the cutter C, through the pawl 14 and the ratchet 11. During this forward movement of the handle-bar, the pawl 14 is held in firm engagement with one of the teeth in the 65 ratchet 11, as shown in Fig. 2, so that the

handle-bar H, the stem 1 and the cutter C, move as a single member. During this operation the teeth 2 of the cutter C cut into and thereby smooth the upper surface of the defective valve-seat v, it being understood 70 that the operator bears down upon the head or knob K to hold the cutter teeth 2 effectively against the valve-seat. The cutter teeth being made of a hard material, such as 75 steel, a few turns of the stem will be sufficient for the teeth to smooth the metal of the valve-seat v which is of softer material, such as brass or a similar composition.

The forward movement of the handle-bar H will, for convenience of operation, be but 80 through a small angle, whereupon the operator will then push the handle-bar H from him to place it in position for the next forward movement. During this return movement of the handle-bar H, as indicated by 85 the arrow b in Fig. 2, the pawl 14 will ride idly over the teeth of the ratchet 11, and there will be no movement of the stem 1 and the cutter C.

The oscillating movement of the handle-bar H to operate the cutter C, enables the tool to be used on a faucet which is close to the wall, as water faucets in houses usually are. In Fig. 1, for instance, the wall from 90 which the faucet F projects, is diagrammatically indicated by the dotted lines W. In order to make the drawings clear, I have shown the handle-bar H as extending beyond the wall W from which the faucet F projects. No matter how close the valve portion 95 of the faucet is to the wall or any other background, the repair tool of my invention 100 can be properly operated by the oscillating movement of the handle-bar H.

It will be observed from Fig. 1 that the 105 sleeve or tubular portion of the cutter C extends substantially into contact with the inside wall f of the faucet. By this arrangement and construction, the cutter also forms a centralizing bearing or guide during the 110 operation of the tool, thus insuring the proper positioning of the cutter teeth 2 on the valve v. Consequently, the action of the teeth 2 on the valve-seat is rendered uniform.

When it is desired to use my new tool on a faucet which has an interior diameter larger than the diameter of the cutter C, I employ an additional ring R, as shown in Fig. 3. This ring, which is separable from the cutter C and is merely slipped over the 115 same, fills out the space between the cutter and the inside surface f' of the faucet F', whereby the cutter is centralized during its 120 operation.

It will be clear from the foregoing that I 125 have provided an extremely simple and useful tool for the repair of worn or defective valve-seats in faucets and the like. This tool is complete in itself and may form as much a part of the householder's repair 130

outfit, as his hammer, saw, screwdriver, and so forth. Being simple in construction, and the parts being readily put together, my new repair tool may be manufactured and sold at 5 a low cost. If desired, a set of cutters of different sizes may be provided for each tool. These cutters are readily slipped in place on the stem and are quickly removed therefrom.

Although I have shown and described a 10 specific form of construction, it is obvious that changes and modifications in detail may be made by those skilled in the art without departing from the scope of the invention as defined in the appended claims.

Having thus described my invention what 15 I claim as new and desire to secure by Letters Patent of the United States, is:

1. A tool for repairing the valve-seats of faucets and the like, comprising a rotatable 20 stem, a sleeve-member mounted on said stem at the lower end thereof, cutting teeth on said stem at the lower end of said sleeve-member for engaging the valve-seat and smoothing the same when the stem is rotated, said sleeve-member extending substantially into contact with the inside wall 25 of the faucet to constitute thereby a centralizing bearing or guide during the operation of the tool, a ratchet fixed upon said stem 30 above said sleeve-member, a handle-bar rotatably mounted at one end on said stem and having a spring-pressed pawl for engaging the teeth of said ratchet, whereby the forward operation of said handle-bar rotates said stem and cutting teeth, while the reverse or return movement of said handle-bar causes said pawl to ride idly over the teeth of said ratchet, and a head or knob 35 rotatably mounted on the upper end of said stem for holding the tool by hand and exerting the necessary downward pressure on the cutting teeth when the same are moved over the valve-seat.

2. A tool for repairing the valve-seats of 40 faucets and the like, comprising a rotatable stem, a cutter mounted upon the lower portion of said stem, said cutter consisting of a sleeve-member provided at its lower end with cutting teeth for smoothing the valve-seat when the tool is operated, coöperating 45 means on said stem and sleeve-member for fixing the latter against rotary as well as longitudinal movement on said stem, said means being adjustable to permit the ready 50 removal and attachment of said cutter from and to said stem, said sleeve-member extending substantially into contact with the inside 55 wall of the faucet to constitute thereby a centralizing bearing or guide during the operation 60 of the tool, a ratchet fixed upon said stem above said cutter, a handle-bar rotatably mounted at one end on said stem and having a spring-pressed pawl for engaging the teeth of said ratchet, whereby the forward 65 operation of said handle-bar rotates

said stem and cutter, while the reverse or return movement of said handle-bar causes said pawl to ride idly over the teeth of said ratchet, and a head or knob rotatably mounted on the upper end of said stem for holding the tool by hand and exerting the necessary downward pressure on the cutting teeth when the same are moved over the valve-seat.

3. A tool for repairing the valve-seats of 70 faucets and the like, comprising a rotatable stem, a cutter mounted upon the lower portion of said stem, said cutter consisting of a sleeve-member provided at its lower end with cutting teeth for smoothing the valve-seat when the tool is operated, said sleeve-member having a slot or recess at its upper end, a fixed pin or lug on said stem adapted to engage in said slot or recess when the cutter is inserted in place on the stem, said pin-and-slot engagement preventing rotary as well as upward movement of said cutter on 80 said stem, an adjustable screw carried by said sleeve-member for securing the cutter to the stem against downward or separating 85 movement, said adjustable screw permitting ready removal of the cutter from the stem, said sleeve-member extending substantially into contact with the inside wall of the faucet to constitute thereby a centralizing bearing or guide during the operation of the tool, 90 a ratchet fixed upon said stem above said cutter, a handle-bar rotatably mounted at one end on said stem and having a spring-pressed pawl for engaging the teeth of said 95 ratchet, whereby the forward operation of said handle-bar rotates said stem and cutter, while the reverse or return movement of said handle-bar causes said pawl to ride idly over the teeth of said ratchet, and a head or knob 100 rotatably mounted on the upper end of said stem for holding the tool by hand and exerting downward pressure on the cutting teeth when the same are moved over the valve-seat.

4. A tool for repairing the valve-seats of 110 faucets and the like, comprising a rotatable stem, cutting teeth fixed upon said stem at the lower end thereof for engaging the valve-seat and smoothing the same when the stem is rotated, a ratchet fixed upon said stem above said cutting teeth, a handle-bar rotatably mounted at one end on said stem and having a spring-pressed pawl for engaging the teeth of said ratchet, whereby 115 the forward operation of said handle-bar rotates said stem and cutting teeth, while the reverse or return movement of said handle-bar causes said pawl to ride idly over the teeth of said ratchet, a head or knob 120 rotatably mounted on the upper end of said stem for holding the tool by hand and exerting downward pressure on the cutting teeth when the same are moved over the valve-seat, and bearing or guiding means on said 125 130

stem adapted to engage the faucet for centralizing the stem during the operation thereof.

5. A tool for repairing the valve-seats of faucets and the like, comprising a rotatable stem, a cutter mounted upon the lower portion of said stem, said cutter consisting of a sleeve-member provided at its lower end with cutting teeth for smoothing the valve-seat when the tool is operated, coöoperating means on said stem and sleeve-member for fixing the latter against rotary as well as longitudinal movement on said stem, said means being adjustable to permit the ready 10 removal and attachment of said cutter from and to said stem, a ratchet fixed upon said stem above said cutter, a handle-bar rotatably mounted at one end on said stem and having a spring-pressed pawl for engaging 15 the teeth of said ratchet, whereby the forward operation of said handle-bar rotates said stem and cutter, while the reverse or return movement of said handle-bar causes said pawl to ride idly over the teeth of said 20 ratchet, and a head or knob rotatably mounted on the upper end of said stem for holding the tool by hand and exerting the necessary downward pressure on the cutting teeth when the same are moved over the 25 valve-seat.

6. A tool for repairing the valve-seats of faucets and the like, comprising a rotatable stem, a cutter mounted upon the lower por- 30

tion of said stem, said cutter consisting of a sleeve-member provided at its lower end 35 with cutting teeth for smoothing the valve-seat when the tool is operated, said sleeve-member having a slot or recess at its upper end, a fixed pin or lug on said step adapted to engage in said slot or recess when the 40 cutter is inserted in place on the stem, said pin-and-slot engagement preventing rotary as well as upward movement of said cutter on said stem, an adjustable screw carried by said sleeve-member for securing the 45 cutter to the stem against downward or separating movement, said adjustable screw permitting ready removal of the cutter from the stem, a ratchet fixed upon said stem above said cutter, a handle-bar rotatably mounted at one end on said stem and having a spring-pressed pawl for engaging the 50 teeth of said ratchet, whereby the forward operation of said handle-bar rotates said stem and cutter, while the reverse or return movement of said handle-bar causes said 55 pawl to ride idly over the teeth of said ratchet, and a head or knob rotatably mounted on the upper end of said stem for holding the tool by hand and exerting downward pressure on the cutting teeth when the same are moved over the valve-seat.

In witness whereof, I hereunto subscribe my name this 19 day of February, 1918.

AUGUST PANN.
